(57) **CLAIM**

The ornamental design for a table, as shown and described.

DESCRIPTION

FIG. 1 is a perspective view of a table, showing my new design with the feet in a protracted position;

FIG. 2 is a front elevational view of FIG. 1, wherein the rear elevational view is a mirror image thereof;

FIG. 3 is a right-side elevational view of FIG. 1, wherein the left-side elevational view is a mirror image thereof;

FIG. 4 is a top plan view of FIG. 1;

FIG. 5 is a perspective view of a table, showing my new design with the feet in a retracted position;

FIG. 6 is a front elevational view of FIG. 5, wherein the rear elevational view is a mirror image thereof;

FIG. 7 is a right-side elevational view of FIG. 5, wherein the left-side elevational view is a mirror image thereof; and,

FIG. 8 is a top plan view of FIG. 5.

1 Claim, 5 Drawing Sheets
